SLIDE NECKTIE

Henry A. Harry, 415 N. Country Club Drive,
McHenry, Ill.

Filed July 6, 1965, Ser. No. 86,052

Term of patent 14 years

(Cl. D3—16)

FIG. 1 is a front view of a slide necktie, showing my new design; and

FIG. 2 is a side view.

I claim:

The ornamental design for a slide necktie, substantially as shown.
